UNITED STATES PATENT OFFICE.

ARTHUR P. HOLDEN, OF TORONTO, ONTARIO, CANADA.

AUTOMATIC VENDING-MACHINE.

No. 905,317.

Specification of Letters Patent.

Patented Dec. 1, 1908.

Application filed January 4, 1906. Serial No. 294,635.

To all whom it may concern:

Be it known that I, ARTHUR PEART HOLDEN, of the city of Toronto, in the county of York and Province of Ontario, Canada, have invented certain new and useful Improvements in Automatic Vending-Machines, of which the following is a full, clear, and exact description.

This invention relates to an automatic vending machine comprising a magazine, an elevator therein automatically movable towards its delivery end, an ejector, a motor for actuating the ejector, and a coin operated controller for the ejector motor, as hereinafter more fully set forth and more particularly pointed out in the claims.

For a full understanding of the invention reference is to be had to the following description and to the accompanying drawings, in which,

Figure 1 is a front elevation of a four magazine vending machine showing the constructive arrangement of the parts. Fig. 2 is a rear elevation of the construction shown in Fig. 1. Fig. 3 is a plan view of the construction shown in Figs. 1 and 2 looking at it from the top. Fig. 4 is a plan view of the construction shown in the preceding figures looking at it from the bottom. Fig. 5 is a perspective view of one of the magazines. Fig. 5^a is a transverse section of the magazine shown in Fig. 5 taken on the line a—a. Fig. 5^b is a vertical section of the magazine taken on the line b—b Fig. 5. Fig. 6 is a vertical section through one of the motors for the magazine elevators, taken lengthwise of the shaft therefor. Fig. 7 is a vertical section of one of the ejectors taken lengthwise of the shaft therefor. Fig. 8 is a side elevation of the construction shown in Fig. 7. Fig. 9 is a vertical section through one of the motors for the ejecting mechanism taken lengthwise of the shaft therefor. Fig. 10 is a front elevation of the construction shown in Fig. 9. Fig. 11 is a side elevation of the construction shown in Fig. 9. Fig. 12 is a side elevation of one of the coin chutes, showing the constructive arrangement of the controlling mechanism for the ejector motors. Fig. 13 is a side elevation of the coin slot closing mechanism. Fig. 14 is a perspective view of the construction shown in Fig. 13. Fig. 15 is a vertical section of a magazine, magazine elevator and an alternative form of elevator motor.

Like letters of reference refer to like parts throughout the specification and drawings.

Within the cabinet a are four magazines b substantially rectangular in cross section, with apertures c at the upper ends of their front sides, and slots e extending from said apertures to their lower ends to facilitate the placing of the merchandise therein. On the magazine fronts, at the sides of the apertures c and projecting above the bottoms thereof are keepers d⁴. Hinged to the magazine fronts are covers d to close the apertures, said covers being vertically movable on their hinges d³ to rise above the keepers d⁴, and to descend into position behind them, so that said keepers may hold the covers to securely close the apertures or permit them to open as required.

In rear of the magazines are slideways f the interiors of which communicate with the interiors of the magazine by slots g formed through the rear sides of the magazine for that purpose. Contained within the magazines b are elevators h having elevator guides i movable in the slideways f, and connected to the elevator guides i are elevator cords or cables j. The elevator cords or cables extend above the top of the slideways f and are wound on the motor drums k. The motor drums k are revolvably mounted on a stationary shaft l supported above the top of the magazine in rear of the slideways, and each motor drum k consists of two annular side plates k' loosely mounted on the stationary shaft l, a rim m contained between the annular side plates k' and maintained in position therebetween by clamping screws m' which fasten the side plates together, and motor springs o contained between the side plates k' within the rim. One end of each motor spring o is connected to the stationary shaft l and the other end is connected to one of the clamping screws m'. The elevator cords or cables j attached to the elevator guides are wound on the motor drums k and as the magazine elevators descend they unwind from and cause the revolution of the motor drums to automatically wind the motor springs o, so that when the descending force is removed from the magazine elevators the motor springs may unwind themselves and rewind the elevator cords or cables on the motor drums. Spring tensioned detent pins p extending through the lower end of the magazine fronts are employed to 110

hold the magazine elevators inoperative in the magazines until the latter have received their contents.

When the magazines are "charged" the 5 detent pins are released to allow the elevator motors to raise the elevators with their loads towards the tops of the magazines and position the topmost packages opposite the delivery openings b' so that they can be engaged 10 and delivered by the ejectors q as the latter move under the influence of the ejector motors as hereinafter described. Each ejector consists of one or more sets of ejector arms q' , a hub q'' loosely mounted on the stationary shaft r above the top of the magazines and a sprocket wheel v . Formed in the heel of each ejector arm q' is a substantially V-shaped groove s to engage the front edge of the topmost package t in its respective 15 magazine until the commencement of the revolution of the ejectors when said package is engaged and ejected by the toe u of the ejector arm or arms coming into contact with it. When the topmost package has 20 been delivered the remaining packages in the magazine are raised by the elevator moving under the influence of the elevator motor to bring the next package in succession to the one delivered opposite the delivery opening 25 of the magazine, the motion of the ejector being arrested when it has cleared the path of the ascending package so that the V-shaped groove s will receive the top edge of the front of the then topmost package t and 30 by preventing its displacement or removal from the magazine cause it to be retained therein until the next operation of the ejecting mechanism.

Mounted on each ejector hub q'' is a 35 sprocket wheel v which is alined with the sprocket wheel v' loosely mounted on the motor shaft w stationarily supported below the magazines. Rigidly connected to each sprocket wheel v' and revoluble therewith is 40 a pinion wheel x which meshes with a spur wheel y loosely mounted on a stationary shaft z located below the motor shaft w . Each spur wheel y is provided with a pinion wheel y' with which meshes a spur wheel w' 45 loosely mounted on the motor shaft w . The spur wheels w' are driven by motor springs w'' coiled around the motor shaft. The outer ends of the motor springs w'' are fastened to a stationary bar a' and their inner 50 ends are connected to the spur wheels w' so that the unwinding of the motor springs will cause the revolution of the spur wheels w' which motion is transmitted by the pinion wheels y' to the spur wheels y and finally to 55 the pinion wheels x and sprocket wheels v' . Passing around the sprocket wheels v and v' are sprocket chains a'' by which motion is transmitted from the motors to the ejectors during the actuation of the former. To stop 60 the actuation of the motors the sprocket

wheels v' or their pinion wheels x are provided with clutch disks b'' having teeth c'' corresponding in number and location with the ejector arms and engaging the rims of the clutch disks are detent clutches d'' forming part of the controlling levers e'' . The controlling levers e'' are fulcrumed intermediate the detent clutches d'' and their coin engaging ends f'' which project into the paths of the coin chutes g'' so that the coins 70 descending therethrough may engage them and cause the levers to rock upon their fulcrums and release the detent clutches d'' from engagement with the clutch disks. The coin chutes g'' correspond in number and location with the magazines b and are preferably located in rear thereof with their upper ends curved forwardly to the coin slots h'' which are formed through the top of the cabinet a . Movable across the top of the coin slots h'' 80 are pivoted covers i'' actuated by bell crank levers j'' and links m'' having slides o'' movable on the slideways f .

In the operation of the apparatus, a coin is inserted into the machine through a coin slot 90 h'' and descends through the corresponding coin chute g'' to the coin receptacle p'' . During its descent it engages the end f'' of the controlling lever e'' and the force of the impact of the coin upon the lever e'' caused by 95 the momentum of its descent is sufficient to displace the lever from its normal position and trip the detent clutch d'' from its engagement with the tooth of the clutch disk so that the clutch disk b'' can revolve with its pinion 100 wheel v' under the influence of the motion transmitted to it from the corresponding motor spring w'' . During the revolution or partial revolution of the clutch disk, its sprocket wheel v' by means of the sprocket 105 chain a'' causes the revolution of its corresponding sprocket wheel v and ejector. The ejector as previously stated, while inactive holds or prevents the removal of the topmost package by its heel engaging the front 110 edge of the package and during the revolution of the ejector, its toe comes into contact with the rear end of the package and discharges it through the delivery opening b' at the top of the magazine. The teeth c'' of 115 the clutch disk are so timed that when the topmost package has been ejected, the motion of the ejector will be arrested and the heel of the ejector will be positioned to engage the front edge of the topmost package 120 until the ejector has been again set in motion after the insertion of a coin. As the packages are from time to time delivered from the magazine the elevator under the influence of its elevator motor intermittently 125 moves upwardly with its load until the last package has been delivered. When the magazine is empty the elevator rises therein until the elevator guide engages the slide o'' and actuates the link and bell crank lever j'' to 130

position the cover i'' so that it will close the coin slot h'' and prevent the insertion of any further coins into the coin chute corresponding to the empty magazine. To cause the 5 instantaneous reengagement of the detent clutches with the teeth of the clutch disks, tension springs l'' are connected to the controlling levers e'' and to the apparatus to restore the controlling levers to their normal 10 position after being actuated by the inserted coin. Slidably mounted on, and revoluble with the winding shaft z' is a winding pinion wheel z'' to successively engage the spur wheels y and revolve them to wind the motor 15 springs w'' . Instead of using spring motors for actuating the elevators, gravity means consisting of cords r' and weights r'' such as shown in Fig. 15, may be employed for that purpose and it is also possible to actuate the 20 elevators by other classes of motors than those shown or described and such as are in common use, and it is also possible to modify the construction and arrangement of the parts without departing from the nature of the invention, the essential features of which are the employment of a magazine for containing the vendible articles, an elevator therein automatically movable towards its delivery 25 end, an ejector for delivering the vendible articles successively during the successive 30 operations of the machine, means for automatically actuating the elevator, other means for automatically actuating the ejector, and a coin operated controller for the ejector 35 actuating means.

I claim—

1. An automatic machine for vending packets of merchandise comprising a packet carrying elevator, a guideway, a guide for 40 the elevator slidable in the guideway, a shaft, a pulley revoluble on the shaft, means for automatically turning the pulley in one direction, a cord for the elevator passing over the pulley and attached to the elevator guide, 45 an ejector shaft, an ejector comprising a hub part and two arms extending radially from the hub part, each arm having a recess in the heel thereof to receive and engage with the front edge of the packet and lock 50 it on the elevator while the ejecting mechanism is inactive, and means for actuating the ejector.

2. An automatic machine for vending packets of merchandise comprising a packet 55 carrying elevator, a guideway, a guide for the elevator slidable in the guideway, a shaft, a pulley revoluble on the shaft, a volute spring attached at its inner end to the shaft and at its outer end to the pulley, a cord for 60 the elevator passing over the pulley and attached to the elevator guide, an ejector shaft, an ejector comprising a hub part and two arms extending radially from the hub 65 part, each arm having a recess in the heel thereof to receive and engage with the front

edge of the packet and lock it on the elevator while the ejecting mechanism is inactive, and means for actuating the ejector to deliver the packet from the elevator.

3. An automatic machine for vending 70 packets of merchandise comprising a packet carrying elevator, a guideway, a guide for the elevator slidable in the guideway, a shaft, a pulley revoluble on the shaft, means for automatically turning the pulley in one direction, a cord for the elevator passing over the pulley and attached to the elevator guide, an ejector shaft, an ejector comprising a hub part and two arms extending radially from the hub part, each arm having a recess in the 75 heel thereof to receive and engage with the front edge of the packet and lock it on the elevator while the ejecting mechanism is inactive, a clock movement, connecting means between the clock movement and the ejector 80 shaft, a clutch disk driven by the clock movement, and a releasable detent clutch for locking and releasing the clutch disk.

4. An automatic machine for vending 90 packets of merchandise comprising a packet carrying elevator, a guideway, a guide for the elevator slidable in the guideway, a shaft, a pulley revoluble on the shaft, a volute spring attached at its inner end to the shaft and at its outer end to the pulley, a cord for 95 the elevator passing over the pulley and attached to the elevator guide, an ejector shaft, an ejector comprising a hub part and two arms extending radially from the hub part, each arm having a recess in the heel thereof 100 to receive and engage with the front edge of the packet and lock it on the elevator while the ejecting mechanism is inactive, a clock movement, connecting means between the clock movement and the ejector shaft, a 105 clutch disk driven by the clock movement and a releasable detent clutch for locking and releasing the clutch disk.

5. An automatic machine for vending 110 packets of merchandise comprising a packet carrying elevator, a guideway, a guide for the elevator slidable in the guideway, a shaft, a pulley revoluble on the shaft, means for automatically turning the pulley in one direction, a cord for the elevator passing over the pulley and attached to the elevator guide, an ejector shaft, an ejector comprising a hub part and two arms extending radially from the hub part, each arm having a recess in the 115 heel thereof to receive and engage with the front edge of the packet and lock it on the elevator while the ejecting mechanism is inactive, a clock movement, connecting means between the clock movement and the ejector shaft, a clutch disk driven by the 120 clock movement, and a pivoted lever engaging the clutch disk at one end.

6. An automatic machine for vending 125 packets of merchandise comprising a packet carrying elevator, a guideway, a guide for 130

the elevator slidable in the guideway, a shaft, a pulley revoluble on the shaft, a volute spring attached at its inner end to the shaft and at its outer end to the pulley, a cord 5 for the elevator passing over the pulley and attached to the elevator guide, an ejector shaft, an ejector comprising a hub part and two arms extending radially from the hub part, each arm having a recess in the heel 10 thereof to receive and engage with the front edge of the packet and lock it on the ele-

vator while the ejecting mechanism is inactive, a clock movement, connecting means between the clock movement and the ejector shaft, a clutch disk driven by the clock 15 movement, and a pivoted lever engaging the clutch disk at one end.
